COMBINED ADJUSTABLE SUPPORT AND ULTRASONIC TRANSDUCER HOLDER FOR DIAGNOSTIC SCANNERS

Edward P. Meyer, Boulder, and William L. Wright, Longmont, Colo., assignors to Physionic Engineering, Inc., Longmont, Colo., a corporation of Colorado

Filed June 17, 1966, Ser. No. 2,716

Term of patent 14 years

(Cl. D83—1)

FIGURE 1 is a side elevational view of a combined adjustable support and ultrasonic transducer holder for diagnostic scanners showing our new design, the opposite side being substantially the same as the side shown;

FIGURE 2 is a front elevational view thereof;

FIGURE 3 is a rear elevational view with portions fragmentally shown for convenience of illustration;

FIGURE 4 is a top plan view thereof with portions omitted for convenience of illustration; and,

FIGURE 5 is a cross section in an enlarged scale taken along line 5—5 of FIGURE 1.

We claim:

The ornamental design for a combined adjustable support and ultrasonic transducer holder for diagnostic scanners, as shown and described.
